23 Claims. (Cl. 33—77)

1

This invention relates to drawing apparatus employed by draftsmen in making perspective drawings.

There are several well known methods or principles by which perspective drawings may be constructed such as the so-called "vanishing point" method and the "visual ray" method. Manual construction of perspective drawings according to these methods requires considerable time and operator skill. Efforts have been directed toward the building of drawing machines with the object of lessening the time required and simplifying the operations involved in making these drawings. While these efforts have resulted in machines that have succeeded to some degree in shortening the drawing time necessary to manually construct perspective drawings, the machines generally are quite costly, are bulky and cumbersome to handle and to operate, and in several instances must be supplemented by manual graphical construction on the part of the operator.

An object of the present invention is to provide a perspective drawing machine with which accurate perspective drawings may be made from regular plan and elevation views without the aid of construction lines. Other objects of this invention are the provision of a machine that is simple to operate and which requires no special skill in the operator; the provision of a machine which permits the operator to make stereoscopic pairs of perspective drawings substantially simultaneously and rapidly; the provision of a machine which permits the operator to plot all spacial points of an object in the perspective view, including those points on the plan view of the object that lay in or close to the "picture plane"; the provision of a machine which utilizes regular plan and elevation views of the object to be drawn and which permits the plan and elevation views to be properly oriented with respect to the operator and to stand in the same direction; the provision of a machine which includes a minimum number of bars and beams and structural components whereby to facilitate and simplify operation of the machine; the provision of a machine that may be set up and disassembled for storage or shipping rapidly and conveniently; the provision of a machine that is comprised largely of standard parts, and thus may be manufactured economically; the provision of a machine which includes means for incorporating an auxiliary elevation view in addition to the regular elevation view thereby permitting use of additional elevation views when desired; and the pro-

2

vision of a machine which includes means for adjusting all members for alignment.

Other objects of the invention will become apparent from the following description of a preferred form thereof, reference being had to the accompanying drawings in which: Figure 1 is a diagram illustrating the theory of the present invention; Figure 2 is a simplified schematic diagram of a drawing machine embodying the present invention; Figure 3 is a plan view of the drawing machine showing the plan pointer means in the initial setting position; Figure 4 is similar to Figure 3 showing the plan pointer means in a plotting position; Figure 4A shows a pair of perspective drawings constructed with the aid of the drawing machine; Figure 5 is a plan view of a portion of the machine showing the carriage and associated components; Figures 6 and 7 are vertical sections taken substantially on the lines 6—6 and 7—7, respectively, of Figure 5; Figure 8 is an enlarged view of a portion of Figure 6 showing details of the swivel plate assembly; Figures 9, 10 and 11 are vertical sections taken substantially on the lines 9—9, 10—10 and 11—11, respectively, of Figure 5; Figure 12 is a plan view of a portion of the machine showing the slide piece and the connection of the elevation beam to the clamp member; Figure 13 is a vertical section taken on the line 11—11 of Figure 12; Figure 14 is a plan view of a portion of the machine showing the support plate assembly and the support assembly for the elevation beams; Figure 15 is a vertical section taken on the line 15—15 of Figure 14; Figure 16 is a side elevation of a foot pedal employed in connection with construction of stereoscopic pairs of perspective drawings, a portion of the pedal being broken away to show details of construction; and Figure 17 is a schematic view of certain components of the drawing machine showing the position of cords and pulleys.

The perspective drawing machine which embodies the present invention is designed to operate on the revolution principle of graphical construction. This principle will be understood by first considering the actual condition of a human observer viewing a distant object such as a house. The house and the observer both stand on a common base, the ground, and both project upwardly from it into the air. The observer's view of the house, that is, the view which his eye sees, is made up of many separate views of the respective points on the house; the separate views meld together to form the whole picture. Thus, lines of sight or "visual rays" from his eye to the many

points on the object define or outline the picture he sees. This picture is called the "perspective view."

If a perspective drawing machine were constructed to simulate the actual condition of an observer viewing an object, certain of the component parts of the machine would necessarily project above the base plane by a distance representative of the height of the observer's eye above the ground. Such a machine would be difficult to operate and hence impracticable. According to the present invention, however, this machine is made practicable by simply revolving the vertically projected components of the machine into the plane of the base. The part of the machine which represents the observer's eye will then lie substantially in the plane of the base; however, the length of the respective lines of sight or "visual rays" remain unchanged, that is, the length of these rays represent true distances between the observer's eye and points on the object.

Referring now to Figure 1, the object selected for showing the method used in plotting the points in the perspective view is a rectangular prism. It will be understood throughout the description of the machine that objects other than rectangular prisms may be used as the subject of a perspective drawing on my machine. The rectangular prism therefore is illustrative of but one of many objects that may be drawn on my machine and is selected herein for illustration because of its simplicity and for clarity of explanation.

The location in the perspective view T of any point on the prism may be found by applying the following graphical method to the location of point A₁ on the rear corner of the top surface of the prism. A line representing the "picture plane" is first drawn. The plan view P is then orientated with respect to the "picture plane" to the desired angle for making the perspective view. The point E is located by spacing same from the plan view P by a distance representative of the horizontal distance between a human observer and the object being viewed. A line *r* is then drawn to connect the chosen point A₁ on the plan view with point E. The line *r* is the horizontal projection of the "visual ray" from the point of observation to the object.

Point F designates the intersection of line A₁E with an arbitrary vertical reference plane, called a "picture plane," which intersects the base plane along the line PP' between the plan view P and the horizontal projection E of the observation point D. From F, a line *p* perpendicular to the line PP' is drawn. The line *p* locates the position of point A₁ on the perspective view in a direction parallel to the "picture plane"; that is, the exact location of point A₁ on the perspective view lies somewhere along the line *p*.

With the line A₁E drawn, point B is located by laying off on a perpendicular to the line A₁E a distance *h* which represents the height of the point A₁ above the ground or base line. This distance *h* is obtained from a regular elevation view S. The point D is then located by laying off a perpendicular to the line A₁E through the point E, the perpendicular having a length equal to the height of the observation point above the ground or base plane. Thus, the line DE represents the height of the observer's eye above the ground. Points B and D are then connected by a line to complete the trapezoid A₁EDB.

The next step is to lay off a perpendicular to

the line A₁E through point F and extend that perpendicular until it crosses the line BD, thereby locating point C. The length *t* of the line CF represents the height of the point A₁ in the "picture plane" above the base line. By laying off the distance *t* above the base line and on the line *p* which has been drawn previously, the position of point A₁ in the perspective view T is located.

Having thus located one point in the perspective view, the other points may be located in the same manner, the distance DE remaining constant throughout the drawing operation. It will be noted that the height *h* will remain the same for all points on the top of the rectangular prism but that the length *t* of line CF will vary. As other points on the prism at a different distance or height above the base line are to be drawn, the length *h* of the line A₁B is changed accordingly.

Figure 2 is a simple schematic diagram of the proposed perspective drawing machine embodying the present invention. The diagram is shown in three dimensional form, the dotted lines representing components of the machine which normally would project upwardly from the base plane if the actual condition of an observer was to be simulated. Whenever convenient, reference letters indicating the intersection of construction lines in Figure 1 are used in Figure 2 in the description of corresponding component parts of the drawing machine.

The eye of a human observer is represented by D'. The line of sight of the observer's eye to the top of the rectangular prism being viewed is indicated by the line D'B'. The true perspective height of a point on the object will be the height of the point of intersection of the observer's line of sight with the "picture plane" above the base line. This is indicated by the point C', the perspective height being the length of C'F. If the trapezoid D'B'A₁E is revolved about the intersection of the plane of this trapezoid with the base plane, that is, revolved about the line A₁E until the trapezoid lays in the plane of the base, the actual condition of an observer viewing an object is maintained without distortion and without variation or change in the true distances representative of the actual physical observation condition. Thus, the trapezoid DBA₁E is the vertical plane D'E'A₁E revolved into and lying in the horizontal or base plane.

It will be noted that the length of C'F represents the true observed height of the top rear corner of the prism in the "picture plane"; therefore, CF likewise represents the true observed height of this point on the prism. Similarly, for other points on the top of the prism, the length of line CF will represent true observed heights of selected points on the prism above the base plane and in the "picture plane." Changes in the length of the line CF are directly proportional to the differences in observed heights of various points on the prism with respect to a base line. As will be explained in detail later, variations in the length of the line CF are utilized to accomplish the mechanical plotting of points in the perspective view.

Before describing the details of construction of the perspective drawing machine which operates on the above described principle of construction of perspective drawings, it will be helpful to note that the schematic diagram of Figure 2 represents a simplified skeleton of the finished machine. The point E is a pivot point about which the

trapezoid DBA₁E is adapted to pivot. The mechanical components DE and CF and A₁B remain perpendicular to the component EFA₁ during all plotting operations. The intersection of components EA₁ and CF, that is the point F, remains in the "picture plane" during pivotal movements of the components about the point E. The length of components EF, DE, and BA₁ are adjustable. The intersection of components DB and CF, that is the point C, is connected to a tracing element in such a manner that variations in the length of CF produce corresponding variations in the position of the perspective plotting means toward and away from the "picture plane."

APPARATUS

As shown in Figures 3 and 4 the perspective drawing machine is mounted on a flat L-shaped drawing board or base B which is adapted to be supported in an elevated position for convenience for the operator. Extension B' of the drawing board B may be hinged to the main body of the board in order that the same may be folded into a convenient size for storage. An elongated channel shaped main guide bar 1 is removably fastened at its ends to the base B and extends transversely of it. A carriage generally indicated at 2 is supported on the drawing board for movement thereover and along the guide bar 1. A channel member 3 is secured to the right end portion of carriage 2, as viewed in Figures 3, 4 and 5 and extends from the carriage parallel to the base B and perpendicular to the guide bar 1. The channel member 3 moves with the carriage 2 over the base B and supports a stem assembly 4 and an extension bar 5 for movement in directions perpendicular to the guide bar. An elevation ruler 6 and a perspective plotting member 7 are connected to and extend from stem assembly 4 for movement therewith in directions parallel to and perpendicular to the bar 1. The elevation ruler 6 spans a regular elevation view S of the object to be drawn, which view is disposed on or attached to the surface of base B under the ruler 6. The member 7 likewise spans a sheet of drawing paper on which the perspective view T of the sheet is ultimately to be drawn. An auxiliary elevation ruler 8, if desired, may be connected to the upper end of the extension bar 5 as viewed in Figures 3 and 4 to permit an additional regular or auxiliary elevation view S' to be used in conjunction with the regular elevation view S in the construction of the perspective drawing.

Mounted on the left end of the carriage as viewed in Figures 3, 4 and 5 is a swivel plate assembly 9 which is adapted to pivot in a horizontal plane about a vertical axis indicated at 10. Guide rods 11 are connected to the assembly 9 and project therefrom away from carriage 2 parallel to base B. Rods 11 are parallel to each other and support slide piece 12 for sliding movement thereover. A plan beam 13 extends transversely of the carriage and is supported for transverse movement on swivel plate assembly 9. Plan beam 13 therefore is adapted to slide across the carriage 2 as well as to pivot with respect to the carriage about the vertical axis 10. A height rod 14 which is connected to the end of plan beam 13 extends therefrom at a right angle to the longitudinal axis of beam 13, and supports a clamp 15 which is adapted to be moved over and clamped in selected positions on rod 14. A pointer 16 clearly shown in Figure 4, is disposed on the end of the plan beam 13 adjacent the height rod

14, and is used as a means for locating various points on the plan view P of the object to be drawn.

A support plate assembly generally indicated at 17 is removably anchored to extension B' of base B and has a yoke member 18 which pivots in a horizontal plane about a vertical axis indicated at 19. Plan beam 13 is supported by the yoke 18 and is free to swing or pivot about the axis 19 as well as to move in directions transversely of the assembly 17. An elevation rod 20 extends from assembly 17 perpendicular to the longitudinal axis of plan beam 13 and is connected to the assembly 17 so as to pivot about axis 19 along with yoke 18. Rod 20 carries a support assembly 21 whose position on rod 20 is adjustable. Assembly 21 supports elevation beam 22 for pivotal and transverse sliding movement relative to rod 20. Beam 22 extends substantially transversely of guide bar 1 and is pivotally connected at one end to clamp 15. The beam 22 extends through slide piece 12 so as to have a pivotal and sliding connection therewith; that is, slide piece 12 moves along guide rods 11 as a result of a lateral shift of the cross over points of elevation beam 22 and guide rods 11 when pointer 16 is moved to various points on the plan view P. Slide piece 12 is tied by cords 96 and 97 or other suitable means to stem assembly 4 so that movements of the piece 12 on guide rods 11 are exactly duplicated by movements of assembly 4 and consequently ruler 6 and member 7 in directions perpendicular to guide bar 1.

Having briefly described a general layout of my perspective drawing machine it will be helpful to note that some of the mechanical components described above have their counterparts in the schematic diagrams of Figures 1 and 2. For example, the pivotal axis 19 of the swivel plate assembly 9 corresponds to the point F; slide piece 12 corresponds to point C on the schematic diagrams and the variable distance between piece 12 and axis 19 of the swivel plate assembly corresponds to the variable length t of the line CF in Figures 1 and 2. Plan beam 13 represents the line A₁E which is the horizontal projection of the "visual ray" DB; elevation beam 22 represents the "visual ray" DB; height rod 14 corresponds to the line A₁B and the selected position of clamp 15 on height rod 14 is comparable to point B. The pivotal axis 19 of yoke 18 in assembly 17 corresponds to point E and elevation rod 20 corresponds to line DE. The adjustable position of pivot member 21 on elevation rod 20 is represented by the point D. Elevation beam 22 which is pivotally connected to clamp 15 and which crosses guide rods 11 and slidingly and pivotally engages slide piece 12 on rods 11, is represented by the line DB or the "visual ray" which terminates at point B correspondingly to clamp 15, crosses line CF corresponding to rods 11 at point C represented by slide piece 12.

The following is a detailed description of the various components that make up my perspective drawing machine. Referring now to Figures 5 and 9, the main guide bar 1 consists of a straight channel shaped member which extends the full length of the drawing board B and is removably secured thereto at its ends by suitable means such as clamp screws 25, see Figures 3 and 4. The carriage 2 which rides along the main guide bar consists of two channel members 30 and 31 disposed on either side of guide bar 1 and secured together by a plate 32 fastened by

screws or the like to their top sides. The inner legs 33 and 34 of channel members 30 and 31, respectively, are spaced from the sides of the guide bar 1 and antifriction rollers 35, 36, 37 and 38 carried by the channel members 30 and 31 so as to rotate about vertical axes maintain rolling contact with the sides of guide bar 1 to guide the motion of carriage 2 along the guide bar with a minimum of resistance. The carriage 2 is supported for movement on the base B preferably by two sets of antifriction wheels 39, 40, and 41, 42 which rotate about shafts 43 and 44 and 45 and 46, respectively, mounted on opposite ends of channel members 30 and 31. These wheels are disposed to rotate about the horizontal axes of the respective shafts and maintain rolling contact with the surface of the base B. This construction permits carriage 2 to have guided, substantially frictionless movement over the base B.

It will be understood that the rollers described above are constructed so as to minimize frictional resistance between the carriage, guide bar and base. Rollers of this type are also employed on other components of the drawing machine to support and guide same in movements relative to each other and to the base. It is desirable that friction between moving parts of the machine be minimized not only to facilitate operation of the machine but also to increase accuracy in the construction of perspective drawings.

(a) *Elevation ruler and plotting member*

In order to guide movements of the elevation ruler 6 and the plotting member 7 parallel to and transversely of guide bar 1, channel member 3, see Figures 5 and 10, which extends away from guide bar 1 and spaced from base B is connected at one end thereof to the carriage 2. The opposite end of channel member 3 has a supporting wheel 51 rotatably mounted thereon and which is adapted to roll on the top surface of base B to support member 3 for movement over base B in directions parallel to guide bar 1. Member 3 extends under plate 32 of the carriage 2 and is attached to it by three screws. Rollers 53 mounted on the bracket 52 which is attached to channel 31 for rotation about a horizontal axis project slightly above the top surface of plate 32 to support an extension bar 5. Member 3 constitutes a base on which the elevation ruler 6 and the plotting member 7 move toward and away from the carriage 2, as will be described below.

A stem assembly generally indicated at 4 is supported on member 3 for movement thereover in directions perpendicular to guide bar 1. Stem assembly 4 consists of spaced side elements 56 and 57 connected together by a plate 58, see Figures 5, 11 and 17. Elements 56 and 57 are disposed on opposite sides of channel member 3 and spaced slightly therefrom and have rearwardly extending flange portions 59 and 60, respectively, in which recesses are formed to accommodate guide rollers 61 and 62. Rollers 61 and 62 rotate about shafts 63 and 64 connected to flanges 59 and 60 and maintain rolling contact with opposite sides of member 3 to guide movements of assembly 4 therealong. Plate 58 has notches 65 and 66 formed therein to receive wheels 67 and 68 which roll on the top surface of channel member 3 and support stem assembly 4 for movement in directions perpendicular to guide bar 1. This movement is also controlled by two adjustable rollers 69 attached to plate 32.

Elevation ruler 6 which consists of bar 70, a fine wire 71 and space wire supporting posts 72

and 73 is connected to and extends from the stem assembly 4 so as to move therewith. One end of bar 70 is secured to element 56 of stem assembly 4 by suitable means such as screws 74. The other end of bar 70 has a vertically disposed pin 75, having a smooth rounded end 75a in contact with surface B, see Figure 11, to support and permit free movement of the elevation ruler over base B. The ruler 6 spans a regular elevation view S of the object being drawn, the wire 71 serving as a straight edge to facilitate accurate setting of other parts of the machine to correspond to a particular height on the object. The plotting member 7 consists of a bar 76 and plotting guides 77 and 78, see Figures 3 and 4, whose positions on bar 76 are adjustable. Bar 76 is secured at one end to element 57 of the stem assembly by screw means 79 and has a pin 80 similar to pin 75 in ruler 6 at its outer end to support same on base B. Thus, member 7 and ruler 6 may move directly with the stem assembly parallel to channel member 3 and also in directions parallel to the guide bar 1 in response to movements of the carriage 2 therealong. V-shaped recesses 81 and 82 in guides 77 and 78, respectively, guide the point of a marking object, such as a pencil, for the purpose of plotting points on the perspective view on a suitable sheet of drawing paper underlying the plotting member.

In order to utilize an additional and/or auxiliary elevation view in connection with making perspective drawings, an auxiliary elevation ruler 8, shown clearly in Figures 3 and 4, is provided. Ruler 8 is essentially the same as ruler 6 and overlays an auxiliary elevation view S' fastened to base B on the opposite side of the carriage from elevation view S. In order to coordinate movements of auxiliary ruler 8 with movements of stem assembly 4, an extension bar 5 which overlays channel member 3 is connected to plate 58 of the stem assembly by screws 85. The bar 5 is supported on rollers 53 adjacent the carriage 2 so as to move freely in directions perpendicular to the main guide bar in response to similar movements of stem assembly 4. The outer end 5a of the bar 5 is suitably secured to ruler 8 which extends therefrom parallel to ruler 6. A pin 83 similar to pin 75 of ruler 6 is carried by the outer end of ruler 8 and supports same for movement over the base B. The ruler 8 with the wire 83 serving as a straight edge overlies an auxiliary elevation view S' of the object being drawn. Auxiliary ruler 8 functions in the same manner as elevation ruler 6 and provides greater flexibility in the machine by permitting auxiliary elevation views to be used conveniently in the construction of perspective drawings.

In order to effect movements of the stem assembly 4 along channel member 3 in directions perpendicular to the main guide bar 1, a pulley 90 is mounted on channel member 3 remote from the carriage 2, the pulley 90 being mounted so as to rotate about a vertical axis, see Figures 5 and 17. Similar pulleys 91 and 92 are mounted on the carriage 2 near the point of connection of channel member 3 to the carriage. Pulley 91 is spaced from the top of carriage 91 by means of a plate 93 and a spacing block 94. The other end of plate 93 is formed to cover the upper end of a shaft 95 suitably fastened to plate 32 of carriage 2 and about which the lower pulley 92 is disposed to rotate. The axes of pulleys 91 and 92 are aligned in a plane parallel to the longitudinal axis of the main guide bar 1 and, as with pulley 90, have annular V-shaped recesses on their peripheries for receiving cords 96 and 97 there-

around. The ends of cords 96 and 97 are connected to the slide piece 12 and to the stem assembly 4 and are disposed around pulleys 90, 91, 92 and 164, the latter being mounted at the extreme outer end of guide rods 11, see Figures 3, 4 and 17, to effect movement of the stem assembly 4 in directions transversely of the main guide bar in response to movements of the slide piece 12 along guide rods 11. This movement of the stem assembly 4 by cords 96 and 97 will be explained in detail later.

(b) *Swivel plate assembly*

In order to support plan beam 13 for pivotal and sliding movement with respect to the carriage 2 during plotting operations, a swivel plate assembly 9 is mounted on the left end of the carriage as viewed in Figures 3, 4 and 5. The assembly 9 consists of a swivel plate 100, and guide members 101 and 102, each of which is secured by screws or the like to the plate 100. Members 101 and 102 preferably are made of short lengths of aluminum having horizontally disposed legs 103 and 104, respectively, which are fastened to the plate 100. Members 101 and 102 also have vertically disposed legs 105 and 106 respectively, which are laterally spaced so as to receive and guide the plan beam 13 therebetween. Guide rollers 107 and 108 on the members 101 and 102 respectively engage the sides of the plan beam and a transverse supporting roller 109, see Figure 7, carried by a pin between plate 100 and members 101 and 102 engages the underside of the plan beam to facilitate sliding movement of same with respect to the carriage.

Guide rollers 107 and 108 as well as other guide and supporting rollers associated with other components of the machine are mounted thereon by means of eccentric sleeves, adjusting screws and the like which permit the axes of these rollers to be shifted slightly for the purpose of effecting accurate adjustment of same. For example, rollers 108, see Figures 5, 6 and 7, are mounted on eccentric sleeves 108a which have hexagonal shaped heads to facilitate turning same to effect the adjustment rollers 108 against the side of plan beam 13.

As shown in Figure 5, plate 100 is preferably formed with a curved outer edge 100a and a projecting portion 110 about which the plate is adapted to swivel or pivot. The plate 100 is supported for pivotal movement by a roller 111, see Figures 6 and 7, which is journaled in channel member 30 of the carriage 2 and which projects through slots in the members 30 and 32 to supportingly engage the underside of the plate 100. Another roller 112 disposed to rotate about a horizontal axis is mounted on a bracket 113, secured to plate 32 of the carriage and engages the top surface of the plate 100 and in conjunction with roller 111 guides the plate 100 in its pivotal movements.

The projection 110 of the plate 100 is provided with an aperture 114, see Figure 8, through which the shank 116 of a pivot stud 115 is adapted to extend. The upper end of the shank 116 has a flange 117 which abuts the top surface of plate 100 and the lower end of shank 116 is threaded as indicated at 118. The shank 116 of pivot stud 115 also extends through the carriage plate 32 which extends under and is slightly spaced from the swivel plate 100 and through the web 31 (a) of carriage channel member 31. A nut 119 fitted into a recess in the web 31 (a) engages the threaded portion 118 of the pivot stud 115 and

draws the members together. The vertical axis of the pivot stud 115 which coincides with the axis 10 of the assembly 9 is the axis about which swivel plate 100 and consequently the assembly 9 rotates.

In order to guide the cords 96 and 97 through the swivel plate assembly 9 so that the cords at all times throughout the drawing operations remain in the plane of the axis 10, a cord guide post assembly generally indicated at 120 is provided, see Figures 6 and 8. The guide assembly 120 consist of an upper pair of guide rollers 121 and 121a and a lower pair of guide rollers 122 and 122a mounted on and disposed to rotate about the shanks 123 and 124 of screws 125 and 126. The guide rollers 121 and 121a and 122, and 122a are positioned between blocks 127 and 128 and plate 100 through which screws 125 and 126 pass, the blocks serving to properly position the rollers with respect to each other. Rollers 121 and 122 have internally disposed bearings, not shown and are thus free to rotate about the axes of screws 125 and 126 with a minimum of friction. Washers 129 and 130 space the rollers from the blocks.

As shown in Figure 8, the peripheries of rollers 120, 120a and 121, 121a are spaced from each other and equally about the axis 10 of swivel plate 100 thereby defining spaces 131 and 132. The space 131 is sufficiently large to permit cord 97 to pass therethrough while the peripheries of rollers 121, 121a lightly engage the sides of the cord. In like manner the space 132 between rollers 122, 122a is just large enough to permit cord 96 to pass while maintaining light engagement with each of the rollers. With this arrangement and spacing of the guide rollers in the cord guide post assembly 120, cords 96 and 97 will pass through the axis of rotation of swivel plate 100 at all times throughout the operation of the drawing machine, that is, for the various angular positions of the swivel plate assembly about the axis 10. It is of interest to note that the "picture plane" described in connection with Figures 1 and 2 is the vertical plane containing pivot axis 10 as well as the reach of cords 96 and 97 between pulleys 91, 92 and guide post assembly 120. The "picture plane" is parallel to the direction of travel of carriage 2 on guide bar 1 and so pivot axis 10 remains in the "picture plane" at all times during operation of the machine.

A position plate 133, see Figure 6, is disposed in a slot in the underside of the guide bar 1 and secured thereto beneath swivel plate assembly 9. Plate 133 has a forwardly projecting portion 134 having a recess 134a underlying pivot axis 10 of the swivel plate assembly. Recess 134a is vertically aligned with the pivot axis 10 and is of sufficient size to admit plan pointer 16 associated with the plan beam 13. When plan beam 13 is moved so as to position pointer 16 in recess 134a, the vertical axis of the pointer will coincide with an extension of pivot axis 10, and the pointer will lie in the "picture plane." With pointer 16 disposed in recess 134a, the machine is in the initial setting position shown in Figure 3; while the pointer is in this position, adjustment of the position of other components of the machine may be made to adapt the machine to plot points at different heights above the base line. The purpose of the initial setting position will be explained more fully in the description of the operation of the machine.

The end 13a of the plan beam 13 adjacent the

carriage 2 is provided with a post generally indicated at 136 to facilitate movement of the plan pointer 16 during location of points on the plan view P. The post 136 consists of a lower sleeve 137 projecting through an aperture 138 in the plan beam 13; and an upper sleeve 139 secured to the sleeve 137 by screws 140 and 140a and having a flange 139a which may be conveniently grasped in the fingers of the operator. Disposed within the sleeves 137 and 139 is a vertically slidable stud member 142 having an enlarged central bearing portion 141. The upper end of stud 142 is threaded to receive a finger knob 143 by which stud 142 and this pointer 16 may be depressed. A spring 144 is disposed between the upper sleeve 139 and knob 143 concentrically of stud 142 to yieldingly urge the stud 142 upwardly in the post. The other end of the stud member is also threaded and passes through an appropriate aperture in an extension piece 145 to which pointer 16 is fastened. Lock nuts 146 secure extension piece 145 on the stud 142. Pointer 16 is normally urged upwardly away from the top surface of the base B by the action of spring 144 on stud 142. During tracing operations when it is desired to bring pointer 16 in contact with a particular point on the plan view P, knob 143 is depressed against spring 144 and pointer 16 is moved into contact with the plan view.

A block 147 is suitably secured to the underside of the end 13a of plan beam 13 by screws 148 and 148a and has a hole 149 drilled therein perpendicular to the longitudinal axis of plan beam 13 for receiving the end of height rod 14. The height rod 14 is removably retained in hole 149 of the block 147 by a set screw 150. Rod 14 projects from block 147 and is spaced from and substantially parallel to the plane of base B. A clamp member 15, shown in Figures 12 and 13, is supported for movement over and adapted to be clamped at selected positions along the height rod 14. The member 15 has a clamping portion 152 which is slotted at 153 and which has a transverse hole 154 passing therethrough intersecting the slot 153 and through which height rod 14 extends. Projecting upwardly from clamping portion 152 is a post 155 having a flanged portion 155a fastened to the top surface of portion 152 by screws, not shown, and a threaded stud 156 disposed within post 155. The lower end of stud 156 threadedly engages portion 152 of the clamp below the slot 153. Normally, rod 14 fits loosely in hole 154 so that clamp member 15 may be moved to any selected position on rod 14. To secure clamp 15 in position on rod 14, knob 157 and consequently stud 156 are turned about their common vertical axis which results in drawing the slotted portion 152 tightly around rod 14. Knob 157 and post 155 provide a convenient means for manipulation of the clamp by the operator.

The clamp 15 also has an extension portion 158 projecting therefrom which has a pivot hole 159 formed therein. Extension 158 overlays the end of elevation rod 22 and is pivotally connected thereto by a pin 160 disposed in hole 159 of the extension 158 and an aligned hole 161 in the end of elevation rod 22. The extension portion 158 of clamp 15 is adapted to slide under slide piece 12 with the axis of pin 160 in alignment with the axis of pivot sleeve 177 of the slide piece 12 as shown in Figures 12 and 13 when the pointer 16 is in the initial setting position. When pointer 16 is in the initial setting position, the common

axis of pin 160 and sleeve 177 lies in the "picture plane."

The slide piece 12 is supported on and guided for sliding movement along a pair of guide rods 11. These rods, preferably having a circular cross section, are spaced from and parallel to each other and are connected to the swivel plate assembly 9 so as to pivot about the axis 10 thereof. The rods 11 extend outwardly from the assembly 9 substantially parallel to the base B and have their longitudinal axes perpendicular to the longitudinal axis of plan beam 13 at all times during plotting operations. The end portions of rods 11 adjacent the assembly 9 extend through apertures in the legs 105 and 106, see Figures 5, 6 and 7 and are fixed thereby by a clamp block 162. Block 162 is fastened to guide member 101 by suitable means such as screws, and is provided with a pair of holes in which the rods 11 pass and are clamped. The outer ends of rods 11 remote from the assembly 9 are fastened in a link 163. A pulley 164 mounted on link 163 for rotation about a horizontal axis is similar to pulleys 98, 91 and 92 described previously, and acts as a direction reversing means for cord 97.

The slide piece 12 which rides or slides on the guide rods 11 consists of a top plate element 166 connected to a front slide block 167 and rear slide blocks 168 and 169. The blocks 167, 168 and 169 are provided with transverse apertures or holes for slidably receiving guide rods 11 to support the slide piece 12 in movements thereover. Guide rollers 170 and 171 are mounted on a bracket 172 carried by the front block 167, on its underside, the guide rollers being rotatable about vertical axes with their peripheries in contact with opposite sides of elevation rod 22 to actuate slide piece 12 by movement of rod 22 with respect to guide rods 11. Bracket 172 is pivotally connected to the front block 167 by means of a pivot sleeve 177. This construction of the slide piece 12 permits elevation rod 22 to move transversely of the slide piece and at the same time to pivot about the axis of sleeve 177. Stud 178 and lock nuts thereon retain the pivot sleeve in the aperture in the front slide block 167.

An aperture 174 extending through the front block 167 of slide piece 12 parallel to the guide bars 11 is formed to permit cord 96 to pass through the slide piece assembly on its way to the pulley 164. The aperture 174 also extends through the pivot sleeve 177 as shown in Figure 13 so that the cord 96 at all times passes through the axis of pivot sleeve 177. Side plates 175 and 176 are secured to the outer edges of the slide piece 12 and furnish a means for tying the ends of cords 96 and 97 to the slide piece 12. The points of connection of cords 96 and 97 to side plates 175 and 176, respectively, are aligned and lie in the vertical plane of the axis of pivot sleeve 177.

(c) Support plate assembly

The plan beam 13 is supported remote from the carriage 2 on a support plate assembly generally indicated at 17. The support plate assembly 17 is connected to the edge of the drawing board extension B' and not only pivotally and slidably supports plan beam 13 but also includes means to limitedly shift the rear support of plan beam 13 and elevation rod 22 in directions parallel to the main guide bar 1, that is, parallel to the "picture plane," to facilitate the making of stereoscopic pairs of perspective drawings as will be explained more fully below.

Referring now to Figures 3, 4, 14 and 15, the assembly 17 includes a channel member 179 mounted on and extending along the edge of drawing board extension B' and secured thereto by screws 180 which engage opposite sides of the extension B'. A reinforcing channel member 181 is secured in back to back relation with channel member 179 as by screws or other suitable means not shown and thus members 179 and 181 together form an I beam on which the other components of assembly 17 are anchored. Strips 182 and 183 are secured by screws 182a and 183a to and extend transversely of members 179 and 181 and have screws 184 and 185 which bear on extension B' and provide for adjusting the assembly to the base. Screws 180, 184 and 185 have knobs as shown to facilitate tightening and loosening of same by the operator during assembly and disassembly of the machine and removal of same from the drawing board.

A supporting block 186 fastened to the top flanges of members 179 and 181 by screws 186a extends parallel to the edge of drawing board extension B' and has a pair of holes, not shown, drilled transversely therethrough for receiving and supporting rods 187 and 188. Rods 187 and 188 are held tightly in block 186 by set screws, not shown, and thus are fixed in position with respect to the base B'. Rods 187 and 188 are supported to extend transversely of the edge of base B' parallel to guide bar 1 and thus parallel to the "picture plane" and in turn furnish supports for other parts of assembly 17.

The outer ends of rods 187 and 188 pass through a terminal clamping block 189 wherein they are tightly secured by screws 190. Blocks 193 and 193a which serve as a stop means to limit the sliding of yoke 18 on the rods 187 and 188 are mounted on the outer ends of rods 187 and 188 that is, to the right as viewed in Figures 14 and 15, and have transversely drilled holes therein, not shown, which guide the blocks 193 and 193a for movement over the rods 187 and 188. A top plate 194 furnishes a base for movement of supported parts on rods 187 and 188 and is secured at one end to the tops of blocks 193 and 193a and at its other end to similar slide blocks not shown, which are likewise adapted to slide along these rods. The edge of plate 194 underlying plan beam 13 is curved as shown at 194a in dotted lines to provide a supporting surface for a smooth bearing plate 197 on which yoke 18 rests and pivots.

A cylindrical head 192, see Figure 15, is disposed on the underside of top plate 194 and is movable therewith and has a pivot shaft 196 projecting vertically therefrom about which the pivoting action of assembly 17 takes place. The pivot shaft 196 has an enlarged bearing portion 195 which passes through an appropriate aperture in plate 194 which forms a bearing for pivotal movement of shaft 196. The axis of shaft 196 constitutes the pivotal axis 19 about which the rearwardly extending portion of plan beam 13 pivots during operation of the machine. The yoke 18 has a split end portion 18a which is non-rotatably clamped to the enlarged portion 195 of shaft 196 by screw 198. The yoke 18 is recessed as shown at 193 to permit the mounting of supporting rollers 200 which contact the underside of plan beam 13 to support and to facilitate sliding of the same over the assembly 17. A block 201 is secured by screws 201a to the underside of the inner end of yoke 18, that is, the left end of yoke 18 as viewed in Figure 5, to furnish an inter-

mediate support and adjustment for elevation rod 20 which is also held in the cylindrical head 192 of the pivot shaft by a set screw. Thus, the yoke 18, plate 194 and the pivot shaft 196 are adapted to be moved or shifted over supporting rods 187 and 188 and parallel to the "picture plane."

Yoke member 18 has fixed thereto a pair of laterally spaced vertically extending flange members 202 and 203 between which plan beam 13 extends and is adapted to move. Roller blocks 204 and 205 are secured externally to flanges 202 and 203, respectively, and are provided at their ends with guide rollers 206, 207, 208 and 209 which guide the plan beam 13 in its transverse movement over assembly 17. Roller block 205 is mounted on pivot shaft 196, as shown in Figure 15, and locked thereon by lock nuts 210 to further stabilize the pivoting of plan beam 13 about shaft 196.

In order to limit the amount of movement of the yoke 18 on rods 187 and 188, blocks 193 and 193a are provided as heretofore mentioned. Clamping screws 212 and 213 having knobs 214 and 215, respectively, are threaded through opposite ends of block 193 and are adapted to engage at their inner ends the sides of rods 187 and 188. The purpose of screws 212 and 213 is to permit block 193 and thus the yoke 18 and pivotal axis 19 to be secured at selected positions on rods 187 and 188 between the limits of shifting movement of these parts relative to the stationary base extension B'. Screws 216 and 216a fasten the blocks 193 and 193a, respectively, to the underside of plate 194, and also serve to secure an angle member 217 to block 193. The outer edge 218 of block 193a is adapted to abut clamp block 189 and limit the movement of block 193a and consequently the movement of yoke 18 and the pivot axis in the direction along supporting rods 187 and 188 toward the right as viewed in Figure 15. In like manner, the side surface 219, of block 193 is oriented so as to abut against the side surfaces of support block 189 and the top flange of auxiliary channel member 181 to limit movement of yoke 18 and pivot axis 19 to the left as viewed in Figure 15.

In order to hold the shiftable or movable parts of the assembly 17 in the position shown in Figures 14 and 15, resilient means are employed to urge block 193a into abutting contact with stationary block 189. For this purpose a rod 220 which extends under the drawing board extension B' bears at one end against member 217 at 221. Rod 220 is supported for sliding movement in a guide element 222 secured to a central plate 223 which is connected to channel members 179 and 181 of the assembly 17. A resilient member such as spring 224 is anchored at one end to a stationary flange 225 fastened to channel member 179 and has its other end fastened to a lug 226 which is fixed to and movable with rod 220. An aperture in stationary flange 225 also serves to guide the movement of rod 220 in a direction parallel to rods 187 and 188.

With the above described construction of the support plate assembly 17, rod 220 is movable in directions parallel to support rods 187 and 188 between the limits defined by the abutment of movable block 193a with stationary clamp block 189 at one extreme and the engagement of block 193 with the stationary block 189 at the other extreme. Movement of these parts from right to left as viewed in Figures 14 and 15 stretches spring 224 which urges rod 220 and the movable

parts of the assembly 17 to return to the position shown in Figures 14 and 15.

The purpose of providing for shifting the pivotal axis 19 is to permit simultaneous construction of stereoscopic pairs of perspective drawings. The stops on rods 187 and 188 are adjustable so as to limit the degree of movement of pivot axis 19 to an amount corresponding to the average interocular distance of an observer's eyes, that is, about 2½ inches. When the shiftable parts of assembly 17 are in the position shown in Figures 14 and 15, points on one perspective view T, see Figures 3 and 4, may be located under guide 78 of plotting means 7. When the movable parts of the assembly are shifted against the pressure of spring 224 to the inner limit of travel, points on the companion stereoscopic view T' may then be located under plotting guide 77. Thus, stereoscopic pairs of perspective drawings may be made simultaneously and conveniently.

In order to effect movement of pivot axis 19 as described above without necessitating diversion of the attention of the operator, a foot pedal generally indicated at 230, see Figure 16, is provided. The foot pedal consists of a base plate 231 and a pair of spaced brackets 232, only one of which is shown, at one end of the base plate, and another bracket 233 secured to the other end of the base plate. A pair of spaced channels 234 and 235 project upwardly from the base plate and are secured pivotally to brackets 232 on a pair of pins 236 held by adjustable clamp means 236a. A cross bar 237 is secured to the upper ends of channels 234 and 235 and has an aperture 238 for receiving a threaded bushing 239 to which is secured a hollow tube 240 for guiding a wire 244 into the pedal assembly.

A foot operated channel shaped bar 242 is pivotally connected to bracket 233 and has its other end connected pivotally to a clamp member 243 which is fastened to one end of a wire 244 which extends from the foot pedal to the support plate assembly 17. Wire 244 passes through a flexible conduit, not shown, and is connected at its other end to member 217 of the assembly 17 by nut and bolt means 245, see Figure 14. Wire 244 extends inwardly from angle 217 and through the flexible conduit, one end of which is attached to stationary flange 225. The flexible conduit is looped through a guide member 246 and passes down to the foot pedal 230. Foot bar 242 is suspended above and spaced from base plate 231 by virtue of the tension on the wire 244 caused by spring 224 of assembly 17. When bar 242 is depressed, as by the foot of the operator, wire 244 shifts member 217 to the left as viewed in Figures 14 and 15 which results in movement of the pivot axis 19 of assembly 17 parallel to the "picture plane" and of approximately 2½ inches. As will appear more fully in the description of the operation of my machine, this shift causes a corresponding movement of plotting means 7 in the same direction which properly positions plotting guide 77 for the location of the selected point on the companion perspective view T'.

The elevation rod 20, see Figures 14 and 15 is secured in the cylindrical head 192 by means of a locking screw 250 and extends through block 201. During assembly of the machine, yoke 18 and the cylindrical head 192 are oriented with respect to each other so that the longitudinal axes of rod 20 and plan beam 13 are perpendicular to each other. Elevation rod 20 therefore is arranged to pivot with respect to the base B' about shaft 196 while maintaining perpendicu-

larity with plan beam 13 throughout the operation of the machine. The outer end of rod 20 is supported for movement over base B' on wheels 252 and 253 pivotally carried by support piece 251 which extends transversely of rod 20 and is adapted to be adjustably positioned therealong.

The rearwardly extending portion of elevation beam 22 is supported for movements transversely of and pivotally on rod 20 by a support assembly 21, see Figures 14 and 15. This assembly consists of a member 255 through which rod 20 passes and on which beam 22 is supported and clamps 256 and 257 on rod 20 and on opposite sides of member 255 which have screws 256a and 257a for releasably clamping same to rod 20 to permit adjustment of the position of assembly 21 along rod 20. A short flanged pin 258 is mounted on member 255 and is the element about which pivoting of beam 22 takes place. Guide members 259 and 260 extend transversely of member 255 and are laterally spaced to define a channel through which elevation beam 22 passes. Roller blocks 261 and 262 secured to guide members 259 and 260 are provided with rollers 263, 264, 265 and 266 which roll on the sides of beam 22 to facilitate sliding movement thereof with a minimum of friction. Rollers 267 and 268 are mounted beneath guide members 259 and 260 and support the beam 22. The flange 258a on pivot element 258 overlies a portion of guide members 259 and 260 and secures same for pivotal motion with respect to member 255 and rod 20.

Support assembly 21 therefore furnishes a pivotal and sliding connection between the elevation beam 22 and rod 20 while at the same time guiding movements of the elevation beam so that its longitudinal axis crosses over the axis of rod 20 at a fixed point on rod 20 selectively spaced from the axis 19 of assembly 17.

Figure 17 shows the disposition of the cords 96 and 97 on the various parts of the machine for the purpose of causing stem assembly 4 to move along channel member 3 in exact response to movements of slide piece 12 along guide rods 11 (not shown in Figure 17). Cord 96 is attached at one end to a tie block 270 secured to top plate 53 of stem assembly 4 and is secured at its other end to the right side plate 176 of the slide piece 12. Between these two points of connection, the cord 96 passes around the periphery of pulley 92 on carriage 2 and passes between lower guide rollers 122 and 122a of swivel plate assembly 9. Cord 97 similarly is attached at one end to block 270 on plate 53 of assembly 4 and has its other end tied to the left side plate 175 of slide piece 12. Between these two points of connection, cord 97 passes around pulley 91 on carriage 2, between top guide rollers 121 and 121a of the assembly 9, through aperture 174 in slide piece 12 and around pulley 164 mounted on the end of guide bars 11. When slide piece 12 moves to the right, as viewed in Figure 17 along the guide bars 11 in response to movements of elevation beam 22, cord 97 will be under tension and will exert a pulling force on stem assembly 4 and to move same along channel member 3 in a direction away from the carriage 2. Similarly, movements of slide piece 12 to the left will place cord 96 under tension and cause stem assembly 4 to move toward the carriage 2. As heretofore mentioned the reaches of the cords 96 and 97 between pulleys 92, 91 and guide rollers 121, 121a, 122, 122a, respectively, are at all times aligned and in the same vertical plane which constitutes the "picture plane."

Also, cords 96 and 97 lie in the same vertical plane between their point of passage through rollers 121, 121a, 122 and 122a and their connection to slide piece 12 which plane constitutes a continuation of the "picture plane" when pointer 16 is in the initial setting position as shown in Figure 3.

Operation

To illustrate the operation of my machine in the construction of perspective drawings, it will be convenient to show the procedure for plotting point A₁ on the top rear corner of the prism of which P is a plan view and S a regular elevation view, see Figures 3 and 4. In order to orient the elevation ruler 6, pointer 16 on the end of plan beam 13 is placed in the initial setting position directly under the pivot axis 19 of swivel plate assembly 9, see Figure 3. With pointer 16 so positioned, guide rods 11 are parallel to the "picture plane" and the axis of pivot sleeve 177 of slide piece 12 is aligned with the axis 10 of the swivel plate assembly and also lies in the "picture plane." The elevation ruler 6 and in particular the fine wire 71 thereof is then moved directly over the top edge of the elevation view S on which the elevation of point A₁ is located. This setting of the elevation ruler 6 is effected by movement of clamp 15 along height rod 14, which in turn moves slide piece 12 on rods 11 and finally causes stem assembly 4 to move in response to the pulling action of either cord 96 or 97. When the wire or "hair line" 71 of the elevation ruler is aligned with point A₁ on elevation view S, clamp 15 is locked in position on rod 14 and the machine is ready to plot the location of point A₁ in the perspective view.

The next step consists in placing pointer 16 on the point A₁ in the plan view P of the prism, as shown in Figure 4. This produces two distinct movements on the machine, namely, the carriage 2 is moved to the left and slide piece 12 is moved to a new position on rods 11. The perspective straight edge 7 also moves to the left along with carriage 2 and toward guide bar 1 in response to the movement of slide piece 12. The position of plotting guide 78 on perspective straight edge 7 determines the location of point A₁ in the perspective view which may be marked by a pencil or other marking means inserted through the V-shaped slot 82 in guide 78.

Other points on the prism whose height above the base of the prism is the same as point A₁ for example, points A₂, A₃ and A₄ may be located in the perspective view by moving pointer 16 over each point in the plan view P and marking the location of same in the perspective view as described above. When other points on the prism at a different elevation from point A₁ are to be plotted, the pointer 16 is returned to the initial setting position, clamp 15 is loosened and moved until wire 71 of elevation ruler 6 is aligned with position of the new point or points on the elevation view S. When this is done, the plotting procedure outlined above is followed to plot the points in the perspective view. The plotted points may be connected by means of a pencil to complete the perspective view T.

Although I have described the plotting procedure specifically as including the step of marking points under guide 78, it is also possible to trace the outline of shapes lying in any one horizontal plane. This may be accomplished by tracing the outline of the plan view P for example, with pointer 16 and holding a pencil in

recess 82 of guide 78 and in contact with the surface of the paper on which the drawing is to be traced. All points at the same height or elevation may be traced in this manner, it being necessary to reset the elevation ruler 6 as described above in order to plot other points in planes at different elevations.

In order to construct stereoscopic pairs of perspective drawings, only two steps in addition to those outlined above are needed. The foot pedal 230 shown in Figure 16 and described above is located under the drawing board B preferably on the floor and near the foot of the operator. After each point is plotted under guide 78 of the perspective plotting element 7, the foot bar 242 of pedal 230 is depressed by the foot of the operator which causes the yoke 18 of assembly 17 and the rod 20 to shift approximately 2½ inches to the left as viewed in Figures 3 and 4 and parallel to the "picture plane" while pointer 16 remains on the particular point in plan view P which is being plotted. Since the pivotal axis of support assembly 21 represents the elevated observation point and pivot axis 19 of support plate assembly 17 represents the projection of the observation point in the base plane as seen by one eye, movement of axis 19 parallel to the "picture plane" by an amount equal to the interocular distance of an observer's eyes sets up a condition on the machine representative of the observer viewing the prism through his other eye. The physical effect of this shifting movement is to move the rearward supports of plan beam 13 and elevation beam 22 which in turn move carriage 2 and thus the perspective plotting member 7 to a new position which represents the view in the "picture plane" seen by the other eye of the observer.

After the operator actuates pedal 230, a point in view T' is marked under plotting guide 77. When the pedal is released, the movable components return to their original positions under the pressure of spring 224 in assembly 17 and the machine is ready to plot the next point. This procedure is followed for the plotting of each point in views T and T'. The points as plotted may then be connected by a pencil, the resultant drawings constituting stereoscopic pairs of perspective drawings of the prism. It will be noted that points on drawing T' are plotted at the same time that those of drawing T are plotted without diverting the attention of the operator from the drawing board. The plotting guides 77 and 78 are adjustably spaced 55 apart to effect proper spacing the stereoscopic pairs of drawings T and T'.

The position of support assembly 21 for elevation beam 22 on rod 20, that is, the radial distance between the point on rod 20 over which the longitudinal axis of elevation beam 22 extends and the pivot axis 19 of the support plate assembly 17 is relative to the height of the observation point above the base plane. In other words, the assembly 21 represents the eye of the human observer. It is often times desirable to construct perspective drawings of an object wherein the height of observation is designated, for example, it may be specified that a "ground level" or "below ground level" view, an "eye level" view or a "bird's eye" view of the object be drawn. For this purpose I have constructed my machine so that the position of assembly 21 on rod 20 is adjustably variable which permits the construction of perspective drawings at selected heights of observation.

To illustrate this feature of my invention, I have shown in Figure 4 a point M on rod 29 to which, it will be assumed, assembly 21 is moved so that the longitudinal axis of elevation beam 22 crosses the axis of rod 23 at point M. With assembly 21 so positioned and the steps followed as outlined above to construct perspective drawings and/or stereoscopic pairs of perspective drawings, the stereoscopic pairs of views K and K' of the prism as shown in Figure 4A will result. Since the point M on rod 29 is closer to the pivot axis 19 of assembly 17 than the original and illustrated position of assembly 21 as shown in Figure 4, movement of assembly 21 to point M in effect lowers the height of observation. The perspective drawings T and T' of Figure 4 may, for example, represent a "bird's eye" view of the prism while the drawings K and K' of Figure 4A may represent an "eye level" view of the prism. It will be understood that my machine is capable of being adjusted to different heights of observation both above and below the base plane and other than those which I have illustrated and described.

In event it is desirable to use an additional regular elevation or auxiliary elevation view S' in the construction of the perspective drawing T, the auxiliary elevation ruler 8 is connected to the end of bar 5 so as to span the view S'. The ruler 8 is adjusted on bar 5 so that its wire or "hair line" edge is aligned with a chosen reference point on view S' at the same time that wire 71 of ruler 6 is set at the height of the same point on view S. Ruler 8 is fastened tightly to bar 5 and is thereafter used in the same manner described above in connection with ruler 6.

Another feature of my invention is that the elevation views S and S' and the perspective views T and T' may be oriented so that they stand in the same direction. Furthermore, the perspective views T and T' as constructed according to my invention also stand in the same direction as does the plan view P. This arrangement of views is particularly convenient and helpful to the drawing machine operator by enabling him to better visualize the character of the object being drawn and to facilitate in the proper construction of perspective views.

In event it is desired to remove the drawing machine from the drawing board for storage or shipment, or otherwise, it is necessary that only four thumb screws be loosened to disengage the machine from the drawing board. These screws are guide bar clamp screws 25 that secure each end of guide bar 1 to the base B and screws 180 that secure the support plate assembly 17 to the base extension B'. There are no other clamps or screws required to secure the drawing machine to the base, which feature enables quick and convenient setup and removal of the machine.

Those skilled in the art will appreciate that various changes and modifications may be made in my invention without departing from the spirit and scope thereof. Accordingly it is to be understood that my patent is not limited to the preferred form of the invention described herein, the essential characteristics of my invention being summarized in the following claims.

I claim:

1. In a perspective drawing machine, a base, a carriage supported for rectilinear movement over said base, a plotting member carried by said carriage and movable over said base relative to

5 said carriage, a plan beam and an elevation beam each disposed parallel to said base and each supported on laterally spaced supports for pivotal movement about a pair of common axes and rectilinear movement relative to said base, means for moving said carriage in response to pivotal movement of said plan beam, means for moving said elevation beam in response to movements of said plan beam, and means for translating movements of said elevation beam in directions transversely of said plan beam into movement of said plotting element relative to said carriage.

2. In a perspective drawing machine, a base, a carriage supported for rectilinear movement over said base, a plotting member carried by said base and movable over said base relative to said carriage, a plan beam and an elevation beam each disposed parallel to said base and each supported on laterally spaced supports for pivotal movement about a pair of common axes and rectilinear movement relative to said base, means for moving said carriage in response to pivotal movement of said plan beam, means for moving said elevation beam in response to movements of said plan beam, means for translating movements of said elevation beam in directions transversely of said plan beam into movement of said plotting element relative to said carriage and means for maintaining fixed selected horizontal spacings between the adjacent ends, respectively, of said beams.

3. In a perspective drawing machine, a base, a carriage supported for rectilinear movement over said base, a plotting member carried by said carriage and movable over said base relative to said carriage, a plan beam and an elevation beam each disposed parallel to said base and each supported on laterally spaced supports remote from said carriage for pivotal movement about a common stationary axis and rectilinear movement relative to said base, means for moving said carriage in response to pivotal movement of said plan beam, means for moving said elevation beam in response to movements of said plan beam, means for translating movements of said plan beam in directions transversely of said plan beam into movement of said plotting element relative to said carriage, and means for simultaneously shifting the position of said supports for said beams in substantially the same direction as the path of movement of said carriage.

4. In a perspective drawing machine, a base, a carriage supported for rectilinear movement over said base, a plotting member carried by said carriage and movable over said base relative to said carriage, a plan beam and an elevation beam each disposed parallel to said base and laterally spaced from the other, separate points of support for supporting said beams for pivotal movement about a common stationary axis and rectilinear movement relative to said base, the point of support for said elevation beam being pivotally connected to and selectively horizontally spaced from the point of support for said plan beam, means for moving said carriage in response to pivotal movement of said plan beam, means for moving said elevation beam in response to movements of said plan beam, and means for translating movements of said elevation beam in directions transversely of said plan beam into movement of said plotting element relative to said carriage.

5. The machine according to claim 4 which includes means for selectively horizontally spacing the ends of said beams remote from said common axis in directions perpendicular to the longitudinal axis of said plan beam.

6. A perspective drawing machine comprising a base, a carriage supported on said base for rectilinear movement thereover, a plotting member supported for movement parallel to and perpendicular to the path of movement of said carriage, a plan beam extending parallel to said base and transversely of the path of movement of said carriage, a pivotal support for said plan beam on said base, an elevation beam, a pivotal support for said elevation beam horizontally spaced from and pivotally connected to the plan beam support, means for maintaining fixed selected horizontal spacing between said beams, a slide piece supported for movement in directions parallel to said base and transversely of said plan beam and having a pivotal and sliding connection with said elevation beam, and means for moving said plotting member relative to said carriage in response to movement of said slide piece relative to said plan beam.

7. A perspective drawing machine comprising a base, a carriage supported on said base for rectilinear movement thereover, a plotting member supported for movement parallel to and perpendicular to the path of movement of said carriage, a plan beam extending parallel to said base and transversely of the path of movement of said carriage, a pivotal support for said plan beam on said base, an elevation beam, a pivotal support for said elevation beam, means for connecting said beams comprising a rod disposed to pivot about the pivotal axis of the support for said plan beam in response to similar movement of said plan beam, the pivotal support for said elevation beam being selectively horizontally positioned on said rod, a slide piece supported for movement parallel to said base in directions transversely of said plan beam and having a pivotal and sliding connection with said elevation beam, and means for moving said plotting member relative to said carriage in response to movement of said slide piece relative to said plan beam.

8. A machine for constructing perspective drawings from regular plan and elevation views comprising a planar base on which said views are mounted, a carriage on said base and movable in a straight line thereover, a plotting element supported for movement over said base in directions parallel to and perpendicular to the path of movement of said carriage, a plan beam disposed parallel to said base, point locating means on said plan beam, a horizontally pivotal member for supporting said plan beam remote from said carriage, guide means anchored to said base, said pivotal member being mounted on said guide means and movable therealong in directions parallel to the path of movement of said carriage, means for moving said carriage in response to pivotal movements of said plan beam, an elevation beam, another horizontally pivotal member movable over said base in directions parallel to and transversely of the path of movement of said carriage and adapted to support said elevation beam, means for moving said other pivotal member in response to movement of said first named pivotal member on said guide means, means for co-ordinating movements of said beams, and means for moving said plotting element in directions parallel to and perpendicular

to the path of movement of said carriage in response to movements of said plan beam.

9. A machine for constructing perspective drawings from regular plan and elevation views comprising a planar base on which said views are mounted, a carriage on said base and movable in a straight line thereover, a plotting element supported for movement over said base in directions parallel to and perpendicular to the path of movement of said carriage, a plan beam disposed parallel to said base, point locating means on said plan beam, a horizontally pivotal member for supporting said plan beam, guide means anchored to said base, said pivotal member being mounted on said guide means and movable therealong in directions parallel to the path of movement of said carriage, means for moving said carriage in response to pivotal movements of said plan beam, stops associated with said guide means to limit the movement of said plan beam support member, foot pedal means connected to said plan beam support member to actuate movement of same between the limits defined by said stops, guide means anchored to said base, said pivotal member being mounted on said guide means and movable therealong in directions parallel to the path of movement of said carriage, means for moving said carriage in response to pivotal movements of said plan beam, an elevation beam, another horizontally pivotal member movable over said base and adapted to support said elevation beam, means for co-ordinating movements of said pivotal members, means for co-ordinating movements of said beam, and means for moving said plotting element in directions parallel to and perpendicular to the path of movement of said carriage in response to movements of said plan beam.

10. The machine according to claim 9 in which said plotting element has a pair of laterally spaced marking means for plotting points on stereoscopic pairs of perspective drawings, one of said marking means defining the location of points on one of said perspective drawings when said plan beam support member is positioned at one limit of movement and the other of said marking means defining the location of points of the other perspective drawing when said plan beam support member is positioned at the other of said limits of movement.

11. In a machine of the character described, a planar base, a carriage adapted to move in a straight line over said base, a plotting element, means connecting said plotting element to said carriage for guiding movement of said plotting element in directions parallel to and perpendicular to the path of movement of said carriage, a plan beam, means for supporting said plan beam for pivotal and rectilinear movements relative to said base, point locating means on one end of said plan beam, an elevation beam, means for supporting said elevation beam for pivotal and rectilinear movements relative to said base, means connecting said plan beam to said elevation beam, a guide member carried by said carriage and extending therefrom parallel to said base and perpendicular to the longitudinal axis of said plan beam, a slide piece on said guide member and adapted to move therealong, said slide piece having pivotal and sliding connection with said elevation beam, and means for moving said plotting element in response to movements of said slide piece along said guide member.

12. The machine according to claim 11 in which said guide member and said carriage have

pulley means, said plotting element movement means including cord means connected to said slide piece and said plotting element and engaging said pulley means and effective to move said plotting element in directions perpendicular to the path of movement of said carriage in response to said movement of the slide piece along said guide member.

13. The machine according to claim 12 which includes means for supporting said plan beam for pivotal and transverse movements relative to said carriage, said cord means being disposed to pass through the axis of pivoting of said plan beam relative to said carriage.

14. The machine according to claim 11 which includes a swivel plate mounted on said carriage and adapted to pivot relative to said carriage in a plane parallel to said base, means on said swivel plate to support said plan beam for movement transversely of said plate, and a position plate fixed to said base having a recess therein aligned with the pivotal axis of said swivel plate, said point locating means on said plan beam being positionable in said recess.

15. A machine for constructing perspective drawings from regular plan and regular elevation views, comprising a base, a carriage mounted on said base for movement thereover in a straight line, a plan beam and an elevation beam each supported for simultaneous movement parallel to said base, point locating means on said plan beam for locating points on said plan view, means for co-ordinating movements of said plan beam and elevation beam, a plotting element, an elevation ruler disposed to span said elevation view, said element and said ruler being disposed to extend substantially parallel to the direction of movement of said carriage an elongated rigid member carried by said carriage and adapted to move in directions perpendicular to the path of movement of said carriage, means for connecting said plotting element and said elevation ruler to said rigid member, and means for moving said rigid member relative to said carriage in response to movements of said plan beam and said elevation beam.

16. A perspective drawing machine comprising a base, a carriage supported for straight line movement over said base, a bar supported on said carriage for movement therewith and relative thereto in directions perpendicular to the path of movement of said carriage, a perspective plotting element connected to said bar and extending therefrom parallel to the path of movement of said carriage, an elevation ruler similarly connected to said bar, a plan beam extending parallel to the plane of said base transversely of the path of movement of said carriage, a pivotal support for supporting said plan beam in pivotal and rectilinear movements relative to said base, an element pivotally connected to said carriage and adapted to pivot in a plane parallel to said base, said plan beam being engageable with said element and movable transversely thereof, an elevation beam extending parallel to the plane of said base and disposed in substantially side by side relation with said plan beam, a pivotal support for said elevation beam, a rod connected to the pivotal support for said plan beam and extending therefrom perpendicular to the longitudinal axis of said plan beam, said pivotal support for said elevation beam being releasably connected to said rod, another rod connected to the end of said plan beam remote from the pivotal support therefor and extending from said plan beam in a di-

rection perpendicular to the longitudinal axis thereof, clamp means releasably clamped on said another rod and pivotally connected to the end of said elevation beam, guide rod means connected to said pivotal carriage element and extending therefrom in a direction perpendicular to the longitudinal axis of said plan beam, a slide piece carried by said guide rod means and movable therealong, said slide piece having pivotal and sliding connection with said elevation beam, and cord means connected to said slide piece for moving said bar in directions perpendicular to the path of movement of said carriage.

17. A machine for constructing perspective drawings from regular plan and regular elevation views, comprising a base, a carriage mounted on said base for movement thereover in a straight line, a plan beam and an elevation beam each supported for pivotal and rectilinear movement parallel to said base, an anchor member secured to said base, said pivotal support for said plan beam being slidably connected to said anchor member and movable thereover parallel to the path of movement of said carriage, foot pedal means connected to said plan beam pivotal support to actuate movement of same, point locating means on said plan beam for locating points on said plan view, means for co-ordinating movements of said plan beam and elevation beam, a plotting element, an elevation ruler disposed to span said elevation view, an elongated rigid member carried by said carriage and adapted to move in direction perpendicular to the path of movement of said carriage, means for connecting said plotting element and said elevation ruler to said rigid member, and means for moving said rigid member relative to said carriage in response to movements of said plan beam and said elevation beam.

18. The machine according to claim 3 in which said last named means comprises guide elements supporting said plan beam support for limited transverse movement parallel to the path of movement of said carriage, means to limit said transverse movement of said plan beam support, and means to actuate movement of said plan beam support between the limits of said transverse movement.

19. The machine according to claim 18 in which said plotting member comprises an elongated bar extending parallel to said base and to the path of movement of said carriage, a pair of adjustably spaced plotting guides on said plotting member, said guides locating the position of plot points on stereoscopic pairs of perspective drawings when said plan beam support is located at the respective limits of its movement.

20. The apparatus according to claim 9 which includes a flexible cable connected at one end to said pedal means and at the other end to said plan beam support member whereby actuation of said pedal will move said element in one direction, and spring means connected to said base and said support member urging the latter to move in the opposite direction.

21. A drawing machine for making perspective drawings from regular plan and elevation views by reproducing in perspective the image of a selected three dimensional object referred to a picture plane, comprising a base lying in a plane perpendicular to said picture plane, an elongated guide bar fastened to said base parallel to and spaced from said picture plane, a carriage supported for movement on said guide bar, a plan beam pivotally supported at one end on said base

and having pivotal and sliding connection with said carriage whereby pivoting of the beam about said one end will cause said carriage to move along said guide bar, the pivotal connection between said plan beam and said carriage lying in said picture plane, a point locating element on the other end of said plan beam for selecting points on the plan view to be plotted, said plan beam being movable to position a said point locating element in said picture plane whereby to facilitate plotting of points lying in said picture plane, a plotting member and means to move said plotting member in response to point locating movements of said plan beam.

22. The machine according to claim 21 in which the pivotal connection between said plan beam and said carriage is spaced above said base, said plan beam being laterally offset from both the axes of pivotal connection of same to said carriage and to said base, said point locating element extending outwardly from said plan beam a distance equal to the offset of said plan beam from said axes whereby to facilitate positioning same under said pivotal connection and in the picture plane.

23. In a machine of the character described, a planar base, a carriage adapted to move in a straight line over said base, a plotting element, an elevation ruler, means connecting said plot-

ting element and said elevation ruler to said carriage for guiding movement of same in directions parallel to and perpendicular to the path of movement of said carriage, a plan beam, means for supporting said plan beam for movements parallel to said base, point locating means on one end of said plan beam, an elevation beam, means for supporting said elevation beam for movements parallel to said base, means connecting said plan beam to said elevation beam, a guide member carried by said carriage and extending therefrom parallel to said base and perpendicular to the longitudinal axis of said plan beam, a slide piece movable on said guide member, said slide piece having pivotal and sliding connection with said elevation beam, and means for moving said plotting element and said elevation ruler normal to the direction of carriage movement in response to movements of said slide piece along said guide member.

OLIVER M. STONE.
